UNITED STATES PATENT OFFICE.

EDWARD B. CORCORAN, OF CINCINNATI, OHIO.

ELECTRIC LAMP FOR MOTOR-VEHICLES.

1,125,266.

Specification of Letters Patent.

Patented Jan. 19, 1915.

Application filed February 6, 1914. Serial No. 816,890.

To all whom it may concern:

Be it known that I, EDWARD B. CORCORAN, a citizen of the United States, and a resident of the city of Cincinnati, in the county of 5 Hamilton and State of Ohio, have invented certain new and useful Improvements in Electric Lamps for Motor-Vehicles, of which the following is a full, clear, and exact description, reference being had to the 10 accompanying drawings, forming a part of this specification.

In the use of electric incandescent bulbs in combination with parabolic reflectors, the proper focus of the shaft of light thrown by 15 the lamp so made, is accomplished by shifting the position of the bulb in and out from the center of the reflector.

The obvious method and one extensively heretofore adopted has been by means of an 20 adjusting screw acting directly on the bulb support in a line with the axis of the bulb. This construction necessitates the attachment of the wires from the side, as the adjusting screw interferes with a direct attachment from the end, and in addition to 25 this inasmuch as the stem of the bulb is necessarily of considerable length and it must be provided with a bearing of corresponding length, unless the parts are accurately 30 fitted the adjusting screw is very apt to get out of alinement, making it difficult to operate.

It is to obviate these objections that my 35 invention is directed, and it consists of that certain novel construction and arrangement of parts to be hereinafter pointed out and claimed whereby an adjustment of the bulb is provided from the side, or out of line with the axis of the bulb, and the wire attachment 40 is made in direct alinement with this axis.

In the drawings, Figure 1 is a horizontal section through a lamp constructed according to my invention. Fig. 2 is an enlarged view of the central portion of Fig. 1. Fig. 45 3 is an end elevation of the socket piece.

1 is the back casing, and 2 the parabolic reflector of an electric lamp. An aperture is provided in the exact center of the reflector and in the back casing with the 50 flanges 3 and 4 around said apertures respectively, turned inwardly toward the space between the two parts. In the passageway so formed, supported by the flanges, is placed the socket piece 5, having suitably secured 55 to it a collar 6. This socket piece has an outer portion insulated by the core 7 from

the conductor spring pins 8 inside of the core. The inner construction of this piece is simple and well known in the art. The pins 8 are held apart in tubes 13 of conductive material by springs (not shown) within the tubes, so that when the bulb 9 and the circuit connection piece 10 are in place, they will be pressed by the springs. The metallic ends of the bulb 9 and of the 60 piece 10 have insulated outer and inner conductors, as has the socket piece. Pins 11, 11, in each instance are mounted on these ends and adapted to be forced into the L-slots 12, 12, of each end of the socket piece. 65 The spring pins then hold the parts in place, as is obvious. A screw 14, with a head 15, is inserted through the back casing and screwed into an aperture 16 in the lug 17 on the collar 6. A spring 18 is mounted over 70 this screw and bears against the back casing and the lug 17. When the screw is turned, the force of the spring will hold the screw from unscrewing from the collar piece, and the collar will travel on the screw and the 75 lamp will be advanced or retracted as the 80 case may be.

It can now be seen that a durable, simple and inexpensive means is provided for forcing the bulb of the electric light in and out 85 to obtain the proper focal position, and that the wire connections for the lamp can be readily made in direct alinement with the axis of the bulb.

The advantages of having the circuit connection direct onto the socket piece for holding the bulb and then moving this socket piece, is quite obvious over structures in the art where the socket piece for the bulb is retracted directly, the wires inserted into the 90 back casing of the lamp with proper holding means and then brought around to connect with the bulb socket.

Having thus described my invention, what I claim as new and desire to secure by Letters Patent, is:—

1. In a device of the character described, a reflector shell, and a back casing, a socket piece, one end having a socket for the bulb and the other end having a socket for the 105 circuit connection, flanges at the central point of the shell and the casing for slidably mounting the socket piece, one end of said socket piece lying outside the back casing and one inside the reflector shell, and means 110 for adjustably retaining the socket piece therein.

2

2. In a device of the character described, a reflector shell, and a back casing, a socket piece, one end having a socket for the bulb and the other end having a socket for the 5 circuit connection, flanges at the central point of the shell and the casing for slidably mounting the socket piece, one end of said socket piece lying outside of the back casing and one inside the reflector shell, and means 10 located between the shell and casing for adjustably retaining the socket piece.

3. In a device of the character described, a reflector shell, and a back casing, a socket piece, one end having a socket for the bulb 15 and the other end having a socket for the circuit connection, flanges at the central point of the shell and the casing for slidably mounting the socket piece, one end of said socket piece lying outside of the back casing 20 and inside the reflector shell, a collar mounted on said socket piece, and means for adjustably retaining the collar between the shell and casing.

4. In a device of the character described, 25 a reflector shell, and a back casing, a socket piece, one end having a socket for the bulb

and the other end having a socket for the circuit connection, flanges at the central point of the shell and the casing for slidably mounting the socket piece, one end of said 30 socket piece lying outside of the back casing and inside the reflector shell, a collar mounted on said socket piece, a lug on the collar, and a screw in the back casing and engaging 35 said lug to adjust the position of the collar.

5. In a device of the character described, a reflector shell, and a back casing, a socket piece one end having sockets for the bulb and the other having sockets for the circuit connection, flanges at the central point of 40 the shell and casing for slidably mounting the socket piece, one end of the socket piece lying outside of the back casing and one end inside the reflector shell, a collar mounted on said socket piece, a lug on the collar, and 45 a screw in the back casing and engaging the lug, and a spring between the lug and the back casing, for the purpose described.

EDWARD B. CORCORAN.
